UNITED STATES PATENT OFFICE

WILLIAM E. SHARP, OF CHICAGO, ILLINOIS

NUT

Application filed April 21, 1926. Serial No. 103,567.

My invention relates to nuts and a method of and apparatus for producing the same, and the object of my invention is broadly to provide improved lock nuts which can be 5 economically produced in commercial quantities.

A more specific object of the invention is to provide a method of and apparatus for producing the improved nuts from flat bars 10 of metal as distinguished from a method of and apparatus for producing lock nuts from metal bars rolled with concavo-convex cross-sections although certain features of the invention are not limited to nuts formed from 15 flat bars of metal.

One form of the invention is embodied in lock nuts which are produced from flat bars of metal by apparatus comprising a punch member adapted to cooperate with a die member, the bars being advanced between the 20 punch and die members which are moved relatively to each other to corrugate the bars transversely thereof and simultaneously to punch spaced holes through the bars, after 25 which, predetermined lengths are severed from the bars to provide nut blanks which are subsequently tapped. The nut blanks are then subjected to pressure in such manner that a portion of the screw threads are de- 30 formed without attendant deformation of the tapped hole.

Many other objects and advantages of the construction herein shown and described will be obvious to those skilled in the art from 35 the disclosure herein given.

To this end my invention consists in the novel construction, arrangement and combination of parts herein shown and described, 40 and more particularly pointed out in the claims.

In the drawing, wherein like reference characters indicate like or corresponding parts:

Fig. 1 is a perspective view of a nut embodying the invention;

Fig. 2 is a perspective view of a portion of a flat bar from which nuts embodying the invention may be made;

Fig. 3 is a sectional view through a die and punch embodying the invention;

Fig. 4 is a section through a nut before compression;

Fig. 5 is a section taken through improved apparatus for deforming a portion of the screw threads near one face of the improved 55 nut; and

Fig. 6 is a section taken on line 6—6 of Fig. 1.

It will be understood that the modification of the locking threads is exaggerated, as 60 shown in Fig. 6, to clearly show the combination. Such modification is necessarily slight—much less than the distance between contiguous threads.

It is believed that a complete understanding of the improved method will be had from a description of apparatus employed in practicing the method.

In Fig. 1 of the drawing, I have shown a self-locking nut embodying the invention, 70 the improved nut being designated by the reference character 10 and being preferably formed with a groove 11 formed on one of its faces and with a ridge 12 formed on the opposite face. The nut is provided with a 75 tapped hole or bolt-receiving aperture 13, screw threads being indicated at 14. A portion only of the screw threads 14 are deformed as will hereinafter more fully appear. The deformed threads are preferably near 80 the upper surface and are indicated at 15. The groove 11 and the ridge 12 are preferably so formed upon the faces of the nut that the thickness of the metal in the nut is substantially uniform.

By practising my improved method, a plurality of nuts, such as the one shown in Fig. 1, may be formed from flat bars of metal of substantially uniform rectangular cross-section, a portion of a bar of this type being 90 shown at 18 in Fig. 2. Heretofore it has been the practice to produce nuts having substantially the same conformation as the one shown in Fig. 1 from bars of metal which were rolled in such manner that each bar had 95 a groove somewhat similar to the groove 11 herein extending longitudinally thereof, a ridge similar to the ridge 12 being rolled in the opposite face of the bar. This entails increased expense, the use of special rolls be- 100

ing necessary by the mill and such bars cannot be economically produced unless rolled in relatively large quantities. Another disadvantage of using bars having ridges and grooves rolled therein is that the rolling mills do not deem it profitable at times to devote one of the milling units to the production of bars of this type, causing delays in the manufacture of nuts. Bars of the type shown in Fig. 2 and designated by the reference character 18 are a standard product and generally a sufficient supply of them is kept on hand by the mill so that orders therefor may be filled immediately. However, certain features of the invention are not limited to self-locking nuts 10 produced from flat bars 18 and it is to be understood that the invention is limited to this feature only to the extent indicated in the appended claims.

My improved apparatus for producing the locking nuts 10 from the flat bars 18 is illustrated in Fig. 3 and preferably comprises a punch holder or member 20 having an upwardly projecting post 21 or equivalent part whereby it may be secured to a reciprocatory member of a punch press (not shown). The member 20 is adapted to cooperate with a die block or member 23 positioned upon the bolster plate or the bed plate of the press (not shown). The die block 23 is preferably provided with a plurality of depressions 25 and 26, there being a plurality of depressions 25 and a single depression 26 in the illustrated embodiment of the invention. The depressions 25 conform to the aforementioned ridges 12 provided upon the nuts 10 and the initial depression 26 is preferably of less depth for a purpose which will presently appear. Secured to the punch member 20 is a punch or former 27 having ridges 28 and 29. The ridge 29 is aligned with the recess 26 and the ridge 28 is aligned with one of the recesses 25. The construction is such that when one of the bars 18 is introduced between the punch or former 27 and the die block 23, and the punch 27 is moved forcibly toward the die block 23, the punch and die block will form depressions in the bar corresponding to the depressions 11 in the nuts 10, ridges corresponding to the ridges 12 being simultaneously formed on the reverse side of the bar. In this instance, the ridge 29 and the groove 26 do not completely form the necessary ridges and grooves in the bar but rather deform the bar in such manner that the adjacent ridge 28 and groove 25 may readily complete the operation when the bar is advanced a unit distance to gradually form the flat bar to an ogee shape with the desired curvatures. It is readily understood that after each stroke of the punch member 20, the bar 18 may be advanced so that any one of the ridges formed in the lower side of the bar will occupy the next groove 25 to the left (Fig. 3). This insures

that the ridges and grooves will be uniformly and correctly spaced along the bar.

It will be noted that the grooves and ridges provided in the bar 18 extend transversely thereof and that the bar 18 is in reality corrugated transversely thereof when it is passed through the apparatus.

The means for forming the bolt-receiving apertures 13 in the bars 18 preferably comprises a punch or piercing tool 32 or the equivalent, registering with an aperture 33 provided in the die member 23, the piercing tool 32 being carried by the punch member 20, preferably aligned with the die block, as illustrated, so that its axis intersects the axis or center of the corresponding groove on the die block and bar 18, and being adapted to stamp a slug 34 from said bar each time the member 20 is reciprocated as the bar is advanced.

At 36 I have shown a guide or pilot member depending from the member 20 and aligned with an aperture 37 formed in the die block 23 and the pilot member 36 is preferably provided with a tapered end 38 adapted to enter the aperture formed in the bar 18 by the piercing tool 32. Obviously, the pilot member will accurately position the bar 18 each time it is advanced. Nut blanks, such as indicated at 40, are preferably simultaneously cut from the bar 18 by a cutoff tool 41 secured to the member 20 and adapted to cooperate with the die block 23. It will be noted that the nut blank 40 is substantially of the same conformation as the nut 10 shown in Fig. 1, the nut blank 40 being provided with a ridge 12 and a groove 11 and also with the bolt hole 13.

In the next step of my improved method, the nut blanks 40 are preferably tapped to provide the screw threads 14, as indicated in Fig. 4, after which a portion of the screw threads 14 preferably near the ridge face of the nut are deformed to bring the contiguous threads near that face slightly closer together in order that when the nut is applied to a bolt, the deformed threads 15 frictionally engage the cooperating threads of the bolt to prevent accidental displacement of the nut relative to the bolt by reason of shocks or vibrations. The screw threads 15 may be deformed in various ways, but, in the preferred embodiment of the invention only the portions of the threads proximate the convex face of the nut blank are slightly compressed to bring them closer together and to increase the frictional contact between them and the cooperating bolt threads. Thus, as illustrated in Fig. 5, the nut blank may be positioned upon a suitable anvil 42 having a ridge 43 preferably fitting snugly into the groove provided upon the concave face of the blank. The convex face of the blank may then be slightly compressed by means preferably comprising a

controlled plunger or hammer 44, or the equivalent, which subjects the nut to predetermined pressure preferably affecting only the threads near the convex face of the nut. 5 Obviously, as the pressure is applied to a relatively small area of the convex face, the threads proximate this area will be deformed. Preferably, the convex face of the blank is subjected to a predetermined pressure which 10 will deform those portions of the threads disposed between the dotted lines 45 in Fig. 5. This is advantageous in that the nut blank 40 is not bent and therefore the bolt-receiving aperture is not deformed and the bolt-receiving 15 aperture 13 need not be given an elliptical or other non-circular shape by the piercing tool 32 to compensate for subsequent deformation of the hole. While I have shown a ridge 43 formed upon the anvil 42, I find 20 that in some instances the ridge 43 may be omitted and that the pressure to which the convex face of the blank is subjected may be so accurately adjusted as to sufficiently compress portions of the threads proximate the 25 convex face without attendant bending of the blank.

In the preferred forms of the invention, the deformed threads 15 are not deflected in the manner that they would be if the nut blank itself were bent, but rather the threads 30 15 are crowded toward each other in such manner that the distance between the top of one thread 15 and the top of an adjacent thread 15 is made less. This causes the 35 threads 15 to effectively engage the threads of the bolt to prevent accidental movement of the nut relative the bolt. Also, the threads 15 cooperate with the normal threads 14 to prevent accidental movement of the nut 40 relative the bolt. However, I am limited to this feature of the invention only insofar as is defined in the appended claims.

In practice, the nuts 10 are preferably applied to the bolts in such manner that the 45 threads proximate the concave surfaces thereof first engage the threads of the bolt by the usual finger fit. The nuts will then turn easily upon the bolts until the deformed threads 15 engage the threads of the bolts, 50 whereupon the frictional contact between the nuts and the bolts will be increased, thus insuring a tight fit and preventing accidental displacement between them.

Having thus described my invention it is 55 obvious that various immaterial modifications may be made in the same without departing from the spirit thereof; hence I do not wish to be understood as limiting myself 60 to the exact form, construction, arrangement and combination of parts herein shown and described or uses mentioned.

What I claim as new and desire to secure by Letters Patent is:

65 1. A method of producing bolt nuts, com-

prising bending a flat bar of metal transversely to form aligned grooves and ridges on opposite faces of the bar interspaced by aligned ridges and grooves on opposite faces of said bar, forming bolt-receiving apertures in said bar through said grooves and ridges, cutting the bar in predetermined lengths to form nut blanks, each having a groove and ridge substantially centrally positioned thereof, and screw-threading the walls of the bolt apertures. 70 75

2. A method of producing lock nuts, comprising subjecting a nut blank to bending pressure to form an aligned groove and a ridge transverse the grain of the metal on the 80 opposite faces thereof with those portions of the blank on either side oppositely bent, forming a bolt-receiving aperture in said blank centrally disposed through said groove and ridge, screw-threading said aperture and subjecting the blank while supported along the 85 entire area thereof to pressure to slightly compress the threads near the ridged face.

3. A method of producing lock nuts comprising subjecting a nut blank to pressure to 90 form a groove and a ridge transverse the grain of the metal upon oppositely disposed faces thereof forming a bolt-receiving aperture in said blank, screw-threading said aperture and subjecting a portion of the ridged 95 face of the nut so formed to pressure while supporting the entire grooved face thereof.

4. Apparatus for producing nut blanks comprising means for bending a flat bar of metal alternately in opposite directions transversely thereof, means for forming bolt-receiving apertures in said bar in the direction of bending force, and means for cutting said bar into predetermined lengths. 100

5. Apparatus for producing nut blanks comprising means for corrugating a flat bar of metal transversely thereof producing aligned grooves and ridges on opposite faces of the bar, means for forming bolt-receiving apertures centrally disposed through the 110 grooves and ridges and threading the same, and means for cutting said bar in predetermined lengths to form nuts, each nut including a groove and ridge section. 115

6. Apparatus for producing lock nuts comprising means for corrugating a bar of metal transversely thereof, means for forming bolt-receiving apertures in said bar and means for cutting said bar into parts, each having a 120 bolt-receiving aperture therein. 125

7. Apparatus for producing lock nuts, comprising means for bending a flat bar of metal transversely to provide alternately formed and interspaced aligned grooves and ridges on opposite faces of said bar, mechanism for forming bolt holes through said bar centrally disposed through said grooves and ridges, and means for cutting said bar into parts to 130 form nuts each including a grooved and ridged section.

8. A nut comprising a blank of uniform thickness bent across the grain so that it is convex on its upper surface at its central portion and concave on said surface on either side thereof, and a threaded hole therethrough, the threads adjacent said upper surface being deformed for locking purposes by axial pressure without bending of the nut.
9. A method of forming nuts comprising applying pressure above and below a flat bar to form corrugations extending transversely thereof, advancing said bar after each application, perforating said bar after each advance with the axes of said perforations extending in the direction of pressure in forming said corrugations, and cutting the bar between said perforations into predetermined lengths to form nut blanks of the desired size.
10. A method of forming nuts comprising applying pressure above and below a flat bar to form corrugations extending transversely of the grain in said bar, advancing said bar after each application, perforating said bar after each advance so that the axes of said perforations intersect those of the corrugations in the bar, cutting the bar between said perforations into predetermined lengths, threading the perforations in said cut blanks, and applying pressure to deform some of the threads in said nuts in the direction of the perforations therein.
11. Apparatus for manufacturing nuts, comprising a press with a former adapted to corrugate a flat bar by a plurality of pressing operations, punch and die means for simultaneously forming bolt-receiving apertures in said bar, and means for simultaneously cutting off an end portion of said bar to form nut blanks.
12. Apparatus for manufacturing nuts, comprising a press provided with a former, punch means and cut-off means, all of said means operating simultaneously, whereby when a flat bar is periodically advanced through said apparatus it is first corrugated, then formed with bolt-receiving apertures, and then cut to the proper size to form nut blanks.
- 50 In testimony whereof, I have hereunto signed my name.

WILLIAM E. SHARP.
